UNITED STATES PATENT OFFICE

MICHAEL BULGER, OF BEAVER DAM, WISCONSIN

DESIGN FOR A PLACARD SUPPORT

Application filed May 2, 1930. Serial No. 35,471. Term of patent 14 years.

To all whom it may concern:

Be it known that I, MICHAEL BULGER, a citizen of the United States, residing at Beaver Dam, in the county of Dodge and State of Wisconsin, have invented a new, original, and ornamental Design for Placard Support, of which the following is a specification, reference being had to the accompanying drawing, forming part thereof.

The drawing is a perspective view of my placard support.

I claim:

The ornamental design for a placard support as shown.

MICHAEL BULGER.
